UNITED STATES PATENT OFFICE.

PAUL REISS, OF BERLIN, GERMANY, ASSIGNOR TO BENNO KNECHT, OF BERLIN, GERMANY.

PRINTING-MACHINE.

1.119,118.

Specification of Letters Patent.

Patented Dec. 1, 1914.

Application filed February 4, 1911. Serial No. 606,612.

To all whom it may concern:

Be it known that I, PAUL REISS, a citizen of the German Empire, residing at Berlin, Germany, have invented certain new and useful Improvements in or Relating to Printing-Machines, of which the following is a specification.

The present invention relates to machines capable of producing print similar to type-written matter and it has the characteristic that individual lines of type are automatically and periodically fed to the form thereby enabling circulars or like matter with uniform type in the text but with different type for the headings or other parts to be easily printed. In this manner it is possible to produce a large quantity of printed matter with different forms, but in the same machine and by means of the same ribbon, so that it presents the aspect of a print produced as a whole and by means of type-writing machines. The lines of type which are periodically fed to the form are by preference arranged in individual type frames which are piled up in a container rigidly connected with the machine frame and for each printing operation are automatically delivered one by one to a feed mechanism which conveys them to the printing point. At the printing point the type frames are raised from the conveyer by a special lifting device and moved into printing position in which they remain until the printing rollers have passed them after which they are automatically returned to the conveyer and advanced in order to make room for the next following frame. At the return point of the conveyer the type carrier frames drop off this conveyer.

40 A machine according to this invention is illustrated in the accompanying drawings in which:

Figure 1 is a side view and partial section of the machine. Fig. 2 is a top plan view with the hood and some other parts removed, and Fig. 3 is a front view of the machine. Fig. 4 is a section on the line 4—4 of Fig. 1. Fig. 5 is a section on the line 5—5 of Fig. 1. Fig. 6 is a view of the type frame container. Fig. 7 is a section on the line 7—7 of Fig. 6. Fig. 8 is a plan view of one of the type frames. Fig. 9 is a section on the line 9—9 of Fig. 8 and Fig. 10 is a section on the line 10—10 of Fig. 8.

55 The printing table 2 is mounted on a

frame 1 and comprises an impression roller 3 arranged within a hood 4. The shaft ends 5 of the impression roller are journaled in glands 6 which are subject to the action of adjustable pressure screws 7. The printing table 2 is adapted to receive a suitable type form 100 (Fig. 5), which contains the type from which the body of the letter or circular is printed. This type form preferably is secured in a recess on the upper side 60 of the table 2 in any suitable manner. At the face ends of the hood 4 are stop pins 8 which in the end positions of the roller engage with arms 9 carrying pawls 10. These pawls coöperate with ratchet wheels 65 70 75 80 85 90 95 100 105 110 115 120 125 130 135 140 145 150 155 160 165 170 175 180 185 190 195 200 205 210 215 220 225 230 235 240 245 250 255 260 265 gaging with lugs 36 on the slide whereby the latter is carried along when the impression roller is moved to and fro. The pins 34, 35 are guided in glands 37, 38 respectively and the latter are connected with the lugs 39 on the hood 4 by set screws 40 (Figs. 1 and 5). These pins moreover are provided respectively with reduced extensions 41, 42 and are under the influence of springs 43, 44 tending to constantly press the corresponding pin into the lug 36 on the slide 29. At their outer ends these coupling pins are each provided with a projection 45 engaging with a notch 46 in the corresponding gland 37 or 38. By withdrawing the pins by means of the roughened heads 47 the hood is thrown out of engagement with the slide 29 and said pins can be locked in this position by rotating them thereby causing the projections 45 to move out of the notches 46 and to bear against the exterior of the glands 37 and 38 respectively.

The machine which is illustrated in the accompanying drawings is continually driven in one direction from an appropriate electric or other motor (not shown) by means of a step-pulley 48. This pulley is fast on a shaft 49 which carries at its other end a worm 50 meshing with a worm wheel 51 (Figs. 1 and 2). This wheel rotates in a housing 52 and is rigidly connected with a bevel wheel 53, which is in constant engagement with two cog-wheels 55, and 56 arranged on a shaft 54. The two cog-wheels are provided on their front faces with coupling teeth 57 adapted to engage with teeth 58 on a coupling sleeve 59. The coupling sleeve 59 is not rotatable on the shaft 54 but is keyed thereon so as to be capable of axial displacement. According to whether the coupling sleeve 59 engages with the teeth 57 of the cog-wheels 55 or 56 the shaft 54 is caused to rotate either in clockwise or counterclockwise direction. Fast on each end of the shaft 54 are sprocket wheels 60 guided over which is a chain 61. This chain at the other end of the machine is carried over sprocket wheels 62 which are adjustably journaled and are freely rotatable on a shaft 63. With the hood 4 this chain 61 is connected in any appropriate manner. According to whether the shaft 54 is rotated to the left or to the right the impression roller is moved in forward or in backward direction. Above the coupling sleeve 59 and rotatably journaled in a bearing 64 is a lever 65 whose one end protruding from the frame 1 is provided with a handle 66. On the lever 65 above the coupling sleeve (Fig. 3) is a pin 67 which during the rocking of the lever engages laterally with an annular groove 68 in the coupling sleeve 59 and displaces the latter to left or to right. As shown in Fig. 2 the lever 65 is provided at each side of the bearing 64 with lugs 69 capable of engaging with a stop 70 arranged on the gland 37 (Figs. 4 and 5).

The forward feed movement of the chain 19 is effected by a ratchet wheel 71 which is fast on the shaft 72 of the sprocket wheel 18. Arranged loosely on this shaft is a disk 73 carrying a pawl 74 which engages with the teeth on the ratchet wheel 71. Pivoted on the disk 73 are two controlling rods 75 and 76 which extend through a lateral rib 77 on the slide 29 (Figs. 1 and 5). These rods are provided with abutments 78 and 79 which during the movement of the roller 3 engage with the rib 77 of the slide 29 and thereby effect an advance movement of the feeding member. The abutments 78 and 79 are so adjusted as to cause the sprocket wheels 17 and 18 to be rotated from the commencement of the feeding movement to the extreme end position of the impression roller through an angle corresponding to the length of one of the links of the chain 19 whereby a fresh printing frame is fed each time precisely over the lifting plate 25. The rod 75 is under the influence of a buffer spring 80 wound around the rear end of the rod and tending to draw the rod back to its initial position when the abutments on the rods 75 and 76 are released.

The printing frames 81 which are fed to the plunger block 24 by the chain 19 are arranged in a frame work or container 82 resting on the support 21. As shown in Figs. 6, 7, 8, 9 and 10 each frame consists of a metal plate provided with slots 83 confined by vertical guide ribs 84. At each end of the slots 83 is a socket 85. Inserted through these sockets are the type carrier pins 86 of which one end 87 is bent over and bears against a lug 88 whereby the types are prevented from dropping out. The types 89 as used by preference for printing machines of this kind are provided with central openings enabling them to be threaded on to the pins 86 side by side. Laterally the types are guided by the ribs 84. Owing to this arrangement the types have a certain resiliency in their frames whereby a particularly good printing effect is obtained. The types thus arranged in the frames are disassembled after use so that new sets can immediately be set up for fresh printing matter. Thus in many establishments it will be only necessary to obtain a machine without type frames which latter can be easily obtained for instance on hire from any of the known advertising agencies where the necessary addresses are set up ready for printing so that they can be directly inserted in the container 82 without further trouble and after use can be returned.

The release of the type frames arranged in the container 82 takes place during the

advance of the chain 19 by means of pins 90 on the sprocket wheel 17 which pins enable always the lowermost frame to be released from the container 82. To this end 5 the column of frames is confined in its lower part by rotatable pins 91 having a portion located between the walls of the container 82 and provided with a recess 92 with which engage lateral lugs 93 on the frames 81. 10 Rigidly secured to the pin 91 is a crank arm 94 carrying a roller 95 capable of engaging with the pins 90. Upon the rotation of the sprocket wheel 17 the arm 94 is so rocked by the pins 90 as to cause the lugs 93 to move out of the recess 92 thereby releasing 15 the lowermost type frame which is free to drop on to the chain 19. During this action the unrecessed upper portion of the pin 91 is turned toward the underside of the next 20 following type frame so that only the lowermost frame is always able to drop on to the conveying chain. Upon the roller 95 being released by the pin 90 the arm 94 rocks back under its own weight whereby the 25 frame column is freed and under the influence of its weight descends so that again the lowermost type frame is caused to engage with the recesses 92. In order to confine with precision the position of the frames 30 81 on the conveying chain 19 the individual chain links are provided with recesses 96 whose width corresponds to that of the lugs 93 whereby a displacement of the type frames during their passage through the 35 machine is rendered impossible. The lower portion of the conveyer chain 19 travels over a guide roller 97 (Fig. 1) whereas the upper part is guided over inclined faces 98 forming part of the guide brackets 23. 40 The operation of the machine is as follows:—By rocking the lever 65 with the aid of the handle 66 one face of the coupling sleeve 59 is thrown into engagement with the teeth 57 of the cog wheel 55 or 56. The 45 shaft 54 together with the sprocket wheels 60 is thus caused to rotate whereby the hood 4 is carried across the printing table. With the hood 4 moves the slide 29 connected thereto by the pins 34, 35 and prevented 50 from tilting by the guide ways 39. During this movement the oblique faces 31 come into engagement with the rollers 27 on the plunger block 24 whereby the latter is raised from the recess 26 and consequently lifts the 55 type frame located at that moment immediately above on the conveyer chain 19 into the path of the impression roller. The horizontal guide portion 33 on the slide 29, insures that the upward movement of the 60 block 24 reaches its end before the impression roller is in engagement with the type frames 81. In this raised position the block remains until the impression roller has passed over it after which it slides in 65 sequence of its weight along the rear guide face 31 back to its lowest position. Should for any cause the plunger block be jammed in its raised position the central roller 28 during the continued movement of the slide 29 is caused to engage with the inner guide 70 face 32 on the latter thereby positively inducing the block to return to its initial position. Toward the end of the movement of the hood 4 the pin 70 on the gland 37 is caused to engage with one of the lugs 69 on 75 the lever 65 whereby the lever is so rocked as to cause the release of the coupling sleeve 59 and to stop the movement of the impression roller. Consequently the printed sheet can be removed and a fresh sheet put 80 in its place during which time the driving motor of the machine need not be stopped. Shortly after the completion of the printing operation the rib 77 on the slide 29 has come into engagement with the abutment 78 85 or 79 on the rod 75 or 76. This causes a rotation to the left of the disk 73 and by means of the pawl 74 a partial rotation of the sprocket wheel 18 to an extent which corresponds to the length of a chain link. 90 A new type frame is thus conveyed over the plate 25 on the block 24 while the type frame preceding it is moved away from the printing position and during the continued motion of the chain and upon reaching the 95 sprocket wheel 18 is caused to drop from the conveyer. During the return movement of the impression roller and after the release of the abutments 78 or 79 from the rib 77 the controlling rods 75 and 76 are thrown 100 back to their initial position by the action of the spring 80. In any second end position of the hood 4—that is to say, at the end of any forward or backward stroke of the impression roller—apart from the movement 105 of the conveyer chain the ribbon action is also controlled. As will be seen one of the stop pins 8 on the hood 4 is caused to engage with the rocking arm 9 at the end of the roller movement whereby the arm 9 is 110 rocked and actuates its pawl 10. The arms 9 are, under the influence of springs, by which they are, after having been rocked, brought back into their normal position. The extent of the throw of the arms 9 depends on the adjustment of the pins 8 with 115 regard to the hood. One of the pawls 10 is always out of engagement with its ratchet wheel 11 so that the ribbon action can only take place in one direction, after any second stroke of the impression roller. As soon as the printed sheet is removed from the machine and the new sheet put in its place the reversing gear is thrown into action by means of the handle 66 in the opposite direction thereby bringing about the return movement of the impression roller. During this movement the printing frame 81 is again raised by the co-operation of the plunger block 24 with the guide faces 31 and a 120 125 130

- feed movement takes place at the end of the roller movement. Upon the beginning of the feed movement the pins 90 on the sprocket wheel 17 pass along beneath the roller 95 on the lever 94 whereby the latter is rocked to such an extent that the lugs 93 are caused to move out of the recess 92 and the type frame is free to drop on to the corresponding link of the conveyer chain 19.
- 10 By the rocking of the pin 91 its solid portion is drawn against the underside of the next following type frame so that only one type frame is freed. After the passage of the pin 90 the arm 94 automatically returns to its vertical position thereby enabling the frame column to descend into the lowermost frame thereof to be engaged in the recess 92.
- In the event of a failure of the driving motor the printing can be effected by hand.
- 20 To this end the hood 4 is arched upwardly in order to offer an appropriate grasp and if desired it may be provided with a fixed handle.

If it is desired to dispense with the automatic feed movement of the type frames in the event of the printed matter requiring no special headings or the like the slide 29 is uncoupled from the hood 4. To this end the pins 34 and 35 are withdrawn by means 80 of the roughened heads 47 from the lugs 36 so that the projections 45 are moved out of their respective notches 46. The respective pins are then slightly rotated in order to prevent the pins from springing back.

25 The slide 29 then remains at a standstill while the machine is continued to be used in the manner above described. When the automatic feed movement of the type frames is again required all that is needed is to 40 again couple the slide 29 with the hood 4. In producing prints wherein the type arranged in a type frame is to be used constantly or repeatedly at several places, the hood 4 together with the slide 29 is moved 45 until the plunger block 24 is in its raised position. In this position the handle 66 is operated to move the reversing gear into the idle running position and the slide is uncoupled from the hood in the manner 50 above stated. It therefore remains in its position beneath the plunger block and the latter itself is held in its raised position and the type frame is in position for printing. During the reciprocation of the impression roller therefore no feed movement of the type frames takes place since the rib 77 on the slide 29 is held out of engagement with the abutments 78 and 79. As soon as the required number of the similar prints is produced the hood 4 is moved over the plunger block 25, the pins 34 and 35 are freed and under the influence of their springs 43 and 44 snap into engagement with the lugs 36 so that the feed mechanism is immediately

thrown into action as soon as the roller 65 reaches its end position.

What I claim is:

1. In a printing machine, a frame adapted to receive a form, impression means movable to and fro over the form and adapted to print at each backward and each forward stroke, and means for feeding a line of type to the form and returning it from said form at each forward and each backward movement of the impression means. 75

2. In a printing-machine, a frame, a type-bed adapted to receive a form, a roller carriage carrying an impression-roller, means for moving the impression-roller to and fro over the form, means for feeding individual lines of type to the underside of the type-bed, and means for feeding the individual lines of type from the underside of the type-bed to the form previous to the printing operation and returning them from the form to the underside of the type-bed after the printing operation. 85

3. In a printing-machine, a frame, a type bed adapted to receive a form, a roller carriage carrying an impression roller, means 90 for moving the impression roller to and fro over the form, and means for automatically and periodically feeding a line of type from the underside of the type bed positively and vertically to the form and returning the 95 same at each backward and each forward movement of the roller carriage.

4. In a printing-machine, a frame, a type-bed adapted to receive a form, a roller carriage carrying an impression-roller, means 100 for feeding individual lines of type to the underside of the type-bed and means controlled by the said roller carriage for feeding the individual lines of type from the underside of the type-bed to the form, previous to the printing operation and returning them from the form to the underside of the type-bed after the printing operation. 105

5. In a printing-machine, a frame adapted to receive a form, a roller carriage movable to and fro over the printing surface and carrying an impression roller adapted to print at each backward and each forward stroke, and means controlled by said roller carriage for automatically and periodically feeding a line of type from the underside of the type bed positively and vertically to the form and returning the same during each backward and each forward movement of the roller carriage. 110 115

6. In a printing-machine, a frame adapted to receive a form, impression means movable to and fro over the type surface and adapted to print at each forward and each backward stroke, a carrying device for 125 an inking ribbon, means for feeding a line of type to the form and returning it from said form during each forward and each

backward stroke of said impression means, and means controlled by the impression means for feeding the inking ribbon at each second stroke of said impression means.

5 7. In a printing machine a frame adapted to receive a form, an impression roller movable to and fro over the form, means for carrying an inking ribbon, means adapted to feed said inking ribbon at the end positions of the impression roller, a spring 10 pressed rail adapted to frictionally engage the impression roller during its forward and backward movement and means for automatically and periodically feeding individual lines of type to the form.

8. In a printing machine, a frame adapted to receive a form, an impression roller movable to and fro over the type surface of the form, an endless feeding member 20 adapted to feed individual lines of type below the form, and a vertically moving member controlled by the impression roller and adapted to move the individual lines of type from the endless feeding member into or 25 out of printing position.

9. In a printing machine a frame adapted to receive a form, an impression roller movable to and fro over the form, a rail resiliently supported by said frame and adapted 30 to frictionally engage the impression roller, means for automatically and periodically feeding individual lines of type to the form and an endless feeding member for conveying the individual lines of type to the feeding 35 point.

10. In a printing machine a frame adapted to receive a form, an impression roller movable to and fro over the form, means for feeding individual lines of type to the 40 form, an endless feeding member for conveying the individual lines of type to the feeding point, a carriage carrying the impression roller, and means carried by said carriage and adapted to feed the endless 45 feeding member at the end positions of the impression roller.

11. In a printing machine, a frame adapted to receive a form, an impression roller movable to and fro over the printing surface 50 face of said form, an aperture in the said frame adapted for the passage of type carrier frames carrying individual lines of type, an endless feeding member for conveying the type carrier frames below the 55 said aperture, a vertically moving member arranged below the said aperture and adapted to carry the type carrier frames through said aperture into or out of printing position, a carriage carrying the impression 60 roller, means carried by said carriage and adapted to feed the endless feeding member at the end positions of the impression roller, and means carried by the roller carriage and adapted to actuate the vertically mov-

ing member at the backward and forward 65 movement of the impression roller.

12. In a printing machine, a frame adapted to receive a form, an impression roller, a receptacle for type carrier frames carrying individual lines of type, an endless feeding member 70 adapted to feed automatically and periodically the type carrier frames from the receptacle below the form, and a vertically-moving member adapted to move the type carrier frames from the endless feeding 75 member into or out of the form.

13. In a printing machine, a frame adapted to receive a form, an impression roller movable to and fro over the form, a receptacle for type carrier frames carrying individual lines of type, an endless feeding member 80 adapted to feed automatically and periodically the type carrier frames from the receptacle below the form, a vertically-moving member adapted to move the type carrier frames from the endless feeding member into or out of the form, means carried by the impression roller and adapted to feed said endless feeding member at the end 85 positions of the impression roller and means carried by said impression roller and adapted to act upon said vertically moving member at the backward and forward movement of the impression roller.

14. In a printing machine, a frame adapted to receive a form, a carrying device for an inking ribbon, feeding means for automatically and periodically feeding individual lines of type to the form, a receptacle for type carrier frames, carrying the individual lines of type, means for automatically and periodically delivering the type carrier frames from the receptacle to the feeding means, impression means movable to and fro over the type surface and adapted 100 to print at each forward and each backward stroke, and means controlled by the said impression means for feeding the said inking ribbon at any second stroke of the said impression means.

110 15. In a printing machine a frame adapted to receive a form, an impression roller movable to and fro over the printing surface, a carrying device for an inking ribbon adapted to hold an inking ribbon between the impression roller and the printing surface, means for automatically and periodically feeding individual lines of type to the form, a receptacle for type carrier frames carrying the individual lines of type, an endless feeding member adapted to convey the type carrier frames to the feeding point and means for automatically and periodically feeding the type carrier frames to the 115 endless feeding member.

120 16. In a printing machine a frame adapted to receive a form, means for automatically and periodically feeding individual lines of

type to the form, a receptacle for type carrier frames carrying the individual lines of type, a pin confining downwardly the lowermost type carrier frame in the receptacle, a recess in the pin for the engagement of the lowermost type carrier frame, a solid face on that pin adapted to engage the lower face of the lowermost but one type carrier frame in said receptacle, an endless feeding member adapted to carry the type carrier frames to the feeding point and means for automatically and periodically rocking said pin.

17. In a printing machine, a frame adapted to receive a form, impression means movable to and fro over the form and adapted to print at each backward and forward stroke, and a plunger block adapted for automatically and periodically carrying individual lines of type to the form at each backward and forward stroke of the said impression means.

18. In a printing machine, a frame adapted to receive a form, an impression roller movable to and fro over the type surface of said form, a roller carriage carrying the said impression roller, a plunger block adapted for carrying individual lines of type to the form, means for feeding the individual lines of type to and upon the said plunger block, and means carried by the roller carriage and adapted to coöperate with the plunger block.

19. In a printing machine, a frame adapted to receive a form, an impression roller, a roller carriage carrying the said impression roller, means for moving the roller carriage to and fro over the printing surface of the said form, a plunger block adapted to carry type carrier frames carrying individual lines of type to the form, means for feeding the type carrier frames to and upon the plunger block, and means carried by the roller carriage and adapted to coöperate with the plunger block at the backward and forward movement of the impression roller.

20. In a printing machine, a frame, a type-bed adapted to receive a form, impression means, an aperture in the said type-bed, a plunger-block located below the said aperture and adapted to periodically carry type-carrier frames carrying individual lines of type through the aperture from the underside of the type-bed to the form and an endless feeding member adapted to convey the type-carrier frames to the underside of the type-bed and to and upon the plunger-block.

21. In a printing machine a frame adapted to receive a form, impression means, a plunger block adapted to feed individual lines of type to the form, a slide adapted to engage with said plunger block, an endless feeding member adapted to convey the individual lines of type to the plunger block and means carried by said slide for periodically feeding said endless feeding member.

22. In a printing machine a frame adapted

to receive a form, impression means, a plunger block adapted to periodically feed individual lines of type to said form, a slide adapted to engage with said plunger block, an endless feeding member adapted to convey the individual lines of type to the plunger block, sprocket wheels carrying said endless feeding member and means adapted to coöperate with said slide and to advance said endless feeding member.

23. In a printing machine a frame adapted to receive a form, impression means, a plunger block adapted to carry type carriers for individual lines of type to the form, an endless feeding member adapted to convey the type carrier frames upon the plunger block, a receptacle for said type carrier frames and means for periodically delivering the type carrier frames from the receptacle to the endless feeding member.

24. In a printing machine a frame adapted to receive a form, impression means, a plunger block adapted to carry individual lines of type to the form, rollers carried by said plunger block and a slide member carried by the impression means and adapted to engage with said rollers so as to raise and lower the plunger block.

25. In a printing machine a frame adapted to receive a form, impression means, a plunger block adapted to automatically and periodically carry individual lines of type to the form, a sliding member constituted by a forwardly and backwardly inclined surface and adapted to coöperate with said plunger block and means for moving the impression means to and fro over the printing surface.

26. In a printing machine a frame adapted to receive a form, impression means, a plunger block adapted to automatically and periodically carry individual lines of type to the form, forwardly and backwardly inclined surfaces, a horizontal portion connecting said inclined surfaces, a slide member supporting said inclined and horizontal surfaces and means carried by the impression means adapted to move said slide member to and fro and into or out of engagement with the plunger block.

27. In a printing machine a frame adapted to receive a form, a plunger block vertically movable between an upper and a lower end position and adapted to automatically and periodically carry individual lines of type to the form, impression means, guide surfaces constituting a slide member, means for moving said slide member into or out of engagement with the plunger block and an auxiliary surface on said slide member adapted to coöperate with the plunger block in the event of the plunger being jammed in its raised position.

28. In a printing machine, a frame adapted to receive a form, impression means, an

aperture in said frame, a plunger block vertically movable below the said aperture and adapted to vertically carry type carrier frames carrying individual lines of type 5 through said aperture to the form, a sliding member carried by the impression means and adapted to coöperate with said plunger block, and means for disconnecting said sliding member from the said impression means.

29. In a printing machine a frame adapted to receive a form, a plunger block adapted to automatically and periodically feed individual lines of type to the form, means for automatically and periodically lowering 10 and lifting said plunger block, impression means and means for locking said plunger block in its raised position.

30. In a printing machine a frame adapted to receive a form, impression means for

automatically and periodically feeding individual lines of type to the form, a reversing gear adapted to move the impression means to and fro over the printing surface, a manually operated lever controlling said reversing gear, lateral projections carried 25 by said lever and means carried by the impression means and adapted to engage the projections of the controlling lever at the end positions of the impression means, so as to throw the reversing gear out of engagement.

In testimony whereof, I affix my signature in presence of two witnesses.

PAUL REISS.
